UNITED STATES PATENT OFFICE

2,002,628

EARTH ANCHOR

Albert B. Chance, Centralia, Mo.

Application June 17, 1932, Serial No. 617,811

4 Claims. (Cl. 189—90)

The present invention relates to earth anchors, and is particularly concerned with earth anchors of the type shown in my prior patent, No. 1,384,825, issued July 19, 1921, for Anchors.

The anchors of this type are installed by boring a hole at substantially right angles to the line of load on the anchor rod member and installing the anchor rod member at right angles to said hole in such manner that it projects into the anchor hole. The anchor is then placed in interlocking engagement with the pointed head of the guy rod, and the anchor is in position to engage the earth at one side of the anchor hole when a pull is applied to the anchor rod, in such manner that the pull is resisted by the undisturbed earth. This undisturbed earth is adapted to resist a pull much more effectively than loose earth which may be placed on top of an anchor, for the reason that the undisturbed earth interacts with a larger area of the earth in the space adjacent the earth which is immediately above the anchor. The effective area of the earth against which the anchor acts is greatly increased when the anchor acts against undisturbed earth.

The anchors of the type described in said patent were provided with approximately cylindrical surfaces for engaging the wall of the hole for the reason that such holes are usually bored in a substantially cylindrical shape, but such anchors were sometimes subjected to difficulties on account of the tendency of the anchor to creep upward in the anchor hole and on account of the tendency of the anchor to tilt as a pull was applied to the anchor rod, causing the anchor to move slightly through the earth.

One of the objects of the present invention is the provision of an improved earth anchor having a greater strength by virtue of its shape and the arrangement of its parts and also adapted to withstand greater loads on the guy rod cable with a minimum weight of metal used in the manufacture of the anchor.

Another object of the invention is the provision of an improved arrangement for the guy rod opening and for guiding the guy rod and anchor into interlocking engagement by virtue of which the assembly of the rod and anchor plate is facilitated so that the anchor plate can be placed upon the rod much more easily than could be accomplished with the devices of the prior art.

Another object of the invention is the provision of an improved type of anchor which has no tendency toward skidding, creeping or tilting under load.

Another object of the invention is the provision of a plurality of modified forms of earth anchors, each constructed of predetermined shape according to mathematical formula, and each having particular advantages with special types of loads, depending upon the particular shape of the anchor.

Other objects and advantages of the invention will be apparent from the following description, and from the accompanying drawings, in which similar characters of reference indicate similar parts throughout the several views.

Referring to the two sheets of drawings accompanying this description,

Fig. 1 is a vertical sectional view taken on the approximate plane of the guy rod, showing the guy rod and the anchor in elevation and the adjacent earth in section;

Fig. 2 is a view in perspective of one of the improved forms of earth anchor constructed according to the present invention, the particular modification in question having substantially triangular side plates;

Fig. 3 is a sectional view taken on the plane of the line 3—3 of Fig. 2, with a fragmentary portion of a guy rod shown in several different positions to show the cooperation between the pointed head of the guy rod and the anchor plate;

Fig. 4 is a top plan view of the anchor plate shown in Fig. 2;

Fig. 5 is a top plan view of another modification of anchor plate, showing a different peripheral shape which may be applied to any of the modified forms of anchor plates described or shown herein;

Fig. 6 is a side elevational view of another modification of the anchor plate, having a curved surface of general conical form, the slope of the cone differing, however, in the direction of the length of the anchor plate from that of the direction of the width;

Fig. 7 is a side elevational view of another modification, showing a substantially parabolic anchor plate surface, and Fig. 7 may also be taken as illustrative of various other types of mathematical curves which may be employed; and

Fig. 8 is a fragmentary sectional view of the lower end of one type of guy rod which may be employed with the present anchor plates.

Referring to Figs. 1 to 3, 10 indicates in its entirety the guy rod which engages the anchor plate 11, disposed in the hole 12. The hole 12 is bored at approximately right angles to the direction of pull upon the cable 13 and guy rod 10,

and the guy rod 10 is placed in a smaller hole bored at right angles to the hole 12, or the guy rod 10 is driven through the earth into the same position.

5 The guy rod 10 may consist of any of the guy rods shown in my prior patents, and it is preferably provided with an eye structure 14 of the type shown in my prior patents and adapted to withstand impact upon the end of the eye in the 10 driving of the anchor into place.

Fig. 1 shows the anchor after the guy rod has been driven in and the anchor plate 11 placed upon it, but before the cable 13 has been pulled up to bring the anchor into firm engagement with 15 the adjacent earth 15.

Referring to Figs. 2 and 3, these are detailed drawings of the anchor plate 11. The anchor plate 11 is preferably substantially oblong in shape, that is, longer in the dimension L than its width, which is indicated by the dimension W. The term "oblong" not only includes the rectangular shape where the anchor is longer than it is wide, but the substantially elliptical shape shown in Fig. 5.

25 Anchors of this type are preferably made in substantially this shape for the reason that they are thus adapted to be used in a hole 12 of smaller diameter than would be the case if the anchor were just as wide as it is long. In other words, the longer type of anchor is adapted to provide a greater area of anchor plate than any other shape for the same size of hole 12.

The anchor plate is preferably provided with surfaces 16, 17 and 18 which slope upward from 35 three of its outer edges 19, 20 and 21 toward the point of attachment of the guy rod 10.

Where the anchor is uniformly curved from one side 16 across the other side 17 and 18, these surfaces gradually merge into each other and become a continuously curved surface, but in the pyramidal form of anchor, shown in Fig. 2, the anchor is provided with hips 22, 23, 24 and 25 extending from each of the corners 26 to 29 of the anchor plate. The corners 26-29 are preferably 45 rounded off, even in the rectangular form of anchor shown in Fig. 2, and in the elliptical type of anchor shown in Fig. 5 the corners are eliminated.

At the center of the anchor plate 11, that is, 50 the apex of the pyramid, cone, or curved surface of the anchor, it is preferably provided with an aperture 30 for passing the head 31 of the guy rod and for receiving the body of the guy rod 10.

Referring to Fig. 8, the guy rod 10 may consist 55 of a substantially cylindrical rod 10 which is provided with a threaded lower end 32 adapted to be threaded into a complementary threaded bore 33 in the pointed head 31. The head of the guy rod 31 comprises a substantially cylindrical metal 60 member which is formed with a conical pointed end 34, a flat upper surface 35, and a frusto-conical surface 36 at its upper end.

In some embodiments of the invention, the 65 pointed head 31 may be an integral part of the guy rod 10, but the two separate parts have particular advantages, since the guy rod 10 may then be used for a number of other purposes. The guy rod 10 is firmly secured to the head 31 by being driven home into the threaded bore 70 33 so that these two parts are fixedly secured together.

In order that the aperture 30 may pass the 75 pointed head 31, it is provided with an enlarged circular portion 37 at a point slightly below the center of the anchor plate in Fig. 4, the cir-

cular portion 37 merging into a slot 38 having opposite parallel walls 39.

The parallel walls 39 communicate with a semi-cylindrical wall 40, which is of a size adapted to receive and engage the body of the guy rod 10, as shown in Fig. 3. The sides or main body of the anchor plate 11 may be made relatively thin 5 in view of the pyramidal, parabolic or approximate conical shape of the anchor plate, thereby saving metal over the devices of the prior art, but the anchor is preferably provided with a thicker body at 41 about the aperture 30.

The body 41 may be formed with a socket 42 having walls 43, 44 on three of the sides of the socket 42 substantially complementary to the upper surfaces of the pointed head 31. The socket 42 is open at 45, its lower end in Figs. 3 and 4 communicating with the guide space 46 that is provided at this end of the anchor for guiding the head of the anchor rod into proper position. 20

Referring to Figs. 2 and 3, the anchor plate 11 is provided with downwardly sloping surfaces 47 at each side. The surfaces 47 are substantially triangular in shape and extend from the corners 28, 29 to points 48, 49 in substantial alignment 25 with the edge of the circular aperture 31.

The flat side wall 44 is joined to the surface 47 by an intermediate tapered surface 50 for guiding the guy rod into the aperture 30.

The triangular plates 47 of the anchor 11 are 30 each joined to a substantially flat triangular plate 51 which is disposed in the general plane of the edges 19-21 of the anchor. The triangular plates 51 are joined by triangular plates 52 at each side to a substantially flat and substantially 35 trapezoidal flat surface 53 which extends outward to the edge 54 of the anchor plate 11 from the aperture 30.

The flat guide plate 53 is disposed substantially 40 below the plane of the edges 19-21 in order to provide a more positive guiding means for the guy rod head than has been provided in anchors of the prior art.

It will be noted that substantially the whole lower end of the anchor plate 11 is brought into 45 play for the purpose of guiding the point of the guy rod into the proper position. Should the point of the guy rod accidentally hit any part of the lower end of the anchor plate between the corners 28, 29, it will be guided into proper position by the surfaces 47, 51, 52 and 53. These guide surfaces from a broad guide groove which tapers in depth from the outer edge 54 of the anchor toward the socket 42, and as the head of the guy rod approaches more closely to the socket, 55 the effect of the guiding surfaces becomes more pronounced.

The present anchor plates are adapted to be placed on the guy rods in the position of Fig. 1 with a minimum amount of effort, as it is not necessary to spot the anchor plate exactly out of the guy rod, but the anchor plate need merely be shoved into such a position that some part of its lower edge registers with the end of the guy rod. 60

The guy rod automatically guides the anchor plate into the proper position, and when the guy rod reaches the aperture 30 the anchor plate is shoved up, on the guy rod. The anchor plate 70 surface 40 then comes into engagement with the cylindrical surface of the guy rod 10, and the plate is permitted to settle down so that the socket 42 surrounds the pointed head 31.

The anchor plates constructed according to the 75

present invention are preferably provided with a substantially flat plate formation 55 at the upper end of the anchor, shown in Figs. 2 to 7. The flat plate 55 is preferably disposed in a plane substantially parallel to the edges 19-21, and it is, therefore, joined with the sloping end plate 17 by means of integral triangular plate formations 56, 57.

The flat plate 55 is provided with an aperture 58, an upwardly projecting tapered lug 59, and a substantially V-shaped groove 60 adapted to engage an anchor placing tool or handle of the type shown in my prior patent.

Referring to Fig. 5, this is an anchor of general pyramidal form, including the views previously described in the substantially rectangular anchor plate of Fig. 2.

I have discovered that the substantially elliptical shape shown in Fig. 5 also has important advantages in the saving of metal and that new and useful results may be accomplished over the prior art by providing an anchor of this shape. Any of the anchors described herein may be made elliptical in plan as well as rectangular.

Referring to Fig. 6, this is an anchor of substantially rectangular or elliptical shape, which embodies the features described with respect to Fig. 2, but is provided with a curved side surface 61 of approximate conical shape.

The side surface 61 curves uniformly from one slope 62 endwise to a different slope 63 sidewise. Since the distance from the side edge 19 to the apex 64 is less than the distance from the end edge 20 to the apex 64 and the altitude is the same, the slope must necessarily be different.

Referring to Fig. 7, this is an illustration of a curved type of anchor embodying the features previously described with respect to the other figures, and the surface 65 of the anchor plate may take the general form of a parabolic surface.

Other curves which may be utilized are curves corresponding to the sides of an ellipse, curves corresponding to a hyperbola, catenary curves, and cycloids.

One of the most important features of an anchor of this type is that the upper surface of the anchor should slope upward from both ends, according to the same law, and upward from both sides, according to the same law, so as to provide a substantially uniformly tapered formation and to balance the forces exerted on both ends of the anchor and tending to tilt the anchor. It will be noted that the sloping surfaces of the anchor are at an acute angle to the edge or periphery and that the angle at the apex is an obtuse angle.

The difficulties caused by the tendency of the anchors of the prior art to creep and tilt are most pronounced when the anchor plate is not disposed in a hole at right angles to the guy rod, but rather at an acute angle. Under these circumstances there is a marked tendency of the anchors of the prior art to creep upward in the hole. This tendency is eliminated by anchors constructed according to the present invention, and the tendency toward tilting is also eliminated by the balancing of the forces, due to the tapered and sloping surfaces of the anchor plate.

It will thus be observed that I have invented an improved anchor which is adapted to eliminate some of the difficulties experienced with the anchors of the prior art. The present anchor is stronger and adapted to withstand more pull on the anchor rod than anchors constructed according to the prior art with the same amount

of metal. The present anchors may, therefore, be constructed of the same strength with a saving of metal. The present anchors are also adapted to be placed in interlocking engagement with the guy rods more easily than the anchors of the prior art. 5

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. In an earth anchor, an anchor plate of substantially oblong shape in plan, said anchor plate being formed with a plurality of substantially triangular side plates joined together along 20 hips and said anchor plate being formed with a centrally located aperture shaped to pass the head of a guy rod member and having a socket for receiving said head on the lower side of said plate, one of said triangular plates being formed 25 with a flat surface disposed substantially parallel to the plane of the periphery of said anchor and having interlocking formations adapted to engage a removable handle for placing the anchor.

2. In an earth anchor, an anchor plate comprising a substantially oblong metal member formed with a centrally located aperture having a socket below said aperture, said aperture being of a size adapted to receive a guy rod and said 35 socket being of a size adapted to receive a guy rod head, said aperture having an enlargement adjacent said socket for passing said head, said anchor sloping from said centrally located socket whereby the forces exerted on said 40 anchor by the earth are balanced on opposite sides of said guy rod and tilting of said anchor is prevented, said anchor having diverging guide surfaces communicating with said aperture located at one end of said oblong anchor, said guide 45 surfaces diverging to substantially a full width of the end of said anchor to facilitate the guiding of a guy rod head into interlocking engagement with said anchor.

3. In an earth anchor, an integral metal member of substantially elliptical outline, said member being provided with a pair of oppositely located flat pyramidal sides joined to side portions located at each end and formed with an aperture in the center, said aperture having an enlargement for passing a head on a guy rod, one of said sides being formed with depending tapering flanges and with a flat portion adapted to engage the head of the guy rod, said flat portion being located below the plane of the opening in said anchor whereby the head of the guy rod may be guided by said flanges and flat portion into position and into engagement with the center of said anchor. 50

4. In an earth anchor, a metallic member having three substantially flat sides joined in substantially pyramidal form and having ridges between said sides, one of said sides having at its end a substantially flat formation located in a plane substantially parallel to the base of the pyramidal metallic member, with diagonally upwardly extending flanges joining said lateral flat portion to said sides, the fourth side of said substantially pyramidal member having downwardly 70 75

extending tapering flanges joined to inwardly extending tapering flanges which carry second downwardly extending tapering flanges leading to a flat portion located substantially in the plane of the base of said substantially pyramidal member, said pyramidal member having a centrally located aperture with an enlargement at

one end for passing the head of a guy rod, said aperture fitting about the shank of said guy rod at its opposite end, and said member being formed with a socket for receiving and holding the head of said guy rod.

ALBERT B. CHANCE.
